UNITED STATES PATENT OFFICE.

WALTER H. CLARK, OF NORTH MARSHFIELD, MASSACHUSETTS.

SOLE LAYING AND ROUNDING MACHINE.

SPECIFICATION forming part of Letters Patent No. 698,257, dated April 22, 1902.

Application filed November 23, 1900. Serial No. 37,413. (No model.)

To all whom it may concern:

Be it known that I, WALTER H. CLARK, a citizen of the United States, residing at North Marshfield, county of Plymouth, State of Massachusetts, have invented an Improvement in Sole Laying and Rounding Machines, of which the following description, in connection with the accompanying drawings, is a specification, like numerals on the drawings 10 representing like parts.

This invention relates to shoe machinery; and it comprises a machine capable of performing the functions ordinarily accomplished by a sole-molding machine, a sole-rounding machine, a sole-laying machine, and a channeling-machine.

It is the common practice in the manufacture of shoes to round or shape the sole of the shoe according to a certain pattern and 20 mold the same between dies to give it the proper shape before it is applied to the shoe. This necessitates handling the sole-blank several times in putting it through the various operations and also necessitates several 25 different types of machines.

It is the object of my invention to provide a single machine which will mold the sole to the last by pressing the sole-blank between a former and the last, and this operation also 30 results in laying the sole or attaching it to the shoe. For this purpose both the sole-blank and the shoe have applied to their contacting faces a coating of suitable adhesive, and the pressure employed in pressing the 35 sole-blank between the former and last also serves to attach said sole-blank to the shoe. While the sole-blank is thus clamped between the former and the last on the jack, the sole is rounded or shaped to the last, and 40 to accomplish this I provide my machine with a suitable knife, mounted on a carriage, and suitable mechanism is provided for causing the knife-carriage to travel around the shoe, the knife being guided in its movement by 45 the last, and thus giving the sole a shape corresponding exactly to the last. Preferably a channeling-knife will also be mounted on said carriage, whereby the rounding and channeling are accomplished at a single operation.

My apparatus therefore embodies a jack to support a last on which is a shoe-upper with the insole applied thereto, a former,

and means to bring the former and last together, so that a sole-blank may be placed on the former and clamped between the same 55 and the shoe on the last, to thereby mold the sole-blank and at the same time attach it to the shoe, combined with a knife-carriage having yieldingly mounted thereon a knife to cut the sole to the proper shape, and means 60 to guide the knife in its movement, so that it will follow the shape of the last. I have therefore provided a single machine by means of which a sole can be molded, attached to the shoe, rounded, and channeled in a single 65 series of operations and without any handling of the sole. I can therefore dispense with the various different machines now used for these various operations and substitute therefor my single machine.

Figure 1 shows in elevation my improved machine. Fig. 2 is an end view thereof. Fig. 3 is a plan view. Fig. 4 is a section on the line xx , Fig. 1. Fig. 5 is a detail showing the clutch-operating mechanism. Figs. 6, 7, 75 and 8 are views of the knife-carriage. Fig. 9 is a detail showing the guide-plate for the knife-carriage. Fig. 10 shows the formers, and Fig. 11 is a detail hereinafter described.

The frame of the machine is designated by 3, 80 and this may be of any suitable construction, it having at its upper end the guides 4, on which the former 5 and its support is mounted for vertical movement, as hereinafter described.

The upper ends of the guides 4 have mounted thereon the cross-head 6, which supports the heel and toe pieces 7 and 8 of the jack, as usual in devices of this class. In this construction, however, instead of having the 90 jack rigidly carried by the cross-head I have supported the same yieldingly thereon, the heel and toe pieces 7 and 8 of the jack having their shanks mounted for vertical sliding movement in holders 9 10, which holders 95 have a horizontal sliding movement in slots 11 and 12 in said cross-head.

The purpose of mounting the holders 9 and 10 in slots is so that the distance between the heel and toe pieces of the jack may be varied 100 according to the size of last on the jack, and any suitable adjusting device may be employed to adjust said holders to the required position, the adjusting device in this instance

being shown as a suitable pivotally-mounted disk 13, having the links 14 pivotally connected thereto and to the holders 9 and 10. By turning the disk 13 by means of the thumb-
5 piece 15 it will be obvious that the distance between the heel and toe pieces of the jack may be varied at will.

Coiled springs 16 surround the shanks of the heel and toe pieces, the said springs abutting at one end against a shoulder 17 on said shanks and at the other end against the holder through which the shanks of the heel and toe pieces of the jack pass.

Suitable means made rigid with the upper 15 ends of the heel and toe pieces of the jack—such, for instance, as pins 18—serve to hold the said heel and toe pieces in the holders 9 and 10.

From the above description it will be seen 20 that my jack is mounted for vertical movement in the cross-head 6 and has a yielding connection therewith, the purpose of which will be hereinafter described, the springs serving to normally hold the jack in its low-
25 ermost position, but allowing it to yield when pressure is applied thereto. In this embodiment of my invention the former is rigidly mounted on a vertically-moving support and is held against motion relative to the support, 30 and suitable means are provided for raising and lowering the former, whereby a sole-blank may be placed on the former when in its lowermost position and the former then carried up against the last, clamping the sole 35 between the same and the last and at the same time molding the sole to fit the last. The support for the former is designated by 20, and the former is shown at 5 and has its upper face properly shaped to form one of the 40 die members for molding the sole-blank, the last acting as the opposing die member, as stated above. Preferably the working face of the former has a facing of rubber or other yielding material 5', which prevents the sole 45 from becoming bruised in the molding. The support 20 has the lugs 22, which are sleeved over the uprights 4, by means of which construction the support and former are properly guided in their vertical movements. As 50 shown, the support 20 has rising therefrom and rigidly secured thereto pillars or posts 27 28, on which is fixedly mounted a plate 29, forming part of the guideway for the knife-carriage, as hereinafter described, the said 55 plate having rigid and preferably integral therewith the lugs 30 31, on which the former 5 is supported.

As seen in Fig. 10 and in dotted lines in Fig. 9, the former has approximately the 60 shape of the rounded sole, and consequently where a left shoe is to have the sole applied thereto the former used must be a left former, as shown in upper part of Fig. 10, and where a right shoe is being made a right former is 65 necessary. In order to adapt the same machine to the manufacture of either right or left shoes, I make my former detachable

from the lugs 30 31, whereby either a right or left former may be used. One convenient way of accomplishing this is to make the upper ends of the lugs 30 31 with square portions 31', which set into suitable sockets in the bottom of the former, as seen in dotted lines in Fig. 1, though I wish it understood that any other suitable way of detachably securing the former to its support may be employed, if desired.

The former and its support are given their vertical movement by means of eccentrics 35, mounted on the counter-shaft 36, the links 80 34, connected to the eccentric-straps, being pivotally connected to the support 20. (See Fig. 1.) The counter-shaft 36 is geared to the main shaft 39 by means of the gears 40 41, which are fast on the counter and main shafts, 85 respectively, and, as seen in Figs. 2 and 4, the gear 41 on the main shaft is one-half the size of the gear 40 on the counter-shaft, whereby a complete rotation of the main shaft will turn the counter-shaft 36 through one-half a rotation. The main shaft 39 is driven by means of the continuously-running belt-pulley 37, which is loosely mounted upon the said shaft, suitable clutch mechanism operating to clutch the pulley to the shaft when it is desired to rotate the same. The clutch comprises the collar 43, having the clutch projections 44 on one face, which coöperate with corresponding recesses on the hub of the driving-pulley 37, the said collar 43 being 90 feathered to the shaft 39, and the spring 49, which surrounds the shaft 39, and is confined between a portion of the frame and said collar, tends to throw the clutch members into engagement. The collar 43, which constitutes the movable clutch member, is normally held out of engagement with the pulley 37 by means of a cam-lug 45, integral with said collar, which is engaged by an offset arm 48, connected to an actuating-lever 46, pivotally mounted in any suitable way to the frame, as at 47. When the lever 46 is depressed by any suitable means, the offset arm 48 is disengaged from the cam-lug 45, when the spring 49, which surrounds the shaft 39, operates to give the 105 collar a longitudinal movement, thereby causing the engagement of the clutch projections and the consequent rotation of the shaft 39. When the main shaft has made a complete revolution and the counter-shaft consequently a 110 half-revolution, the cam-lug 45, moving in the direction of the arrow in Fig. 5, contacts with the inside of the offset arm 48, and thereby moves the collar 43 longitudinally on the shaft, compresses the spring 49, and disengages the clutch members. A suitable spring, such as 50, serves to raise the operating-lever 46, after the same has been depressed, sufficiently to bring the offset arm 48 into the 115 path of the cam-lug 45.

As illustrated in the drawings, the offset arm 48 is mounted upon a separate lever 51, which is pivotally mounted on the frame, and the said lever is connected by means of a link 120

52 to the operating-lever 46, though I would remark that this way of connecting the offset arm 48 to the lever 46 is immaterial, as the arm might be made an integral part of the lever.

5 In Fig. 5 is shown in full and dotted lines the two extreme positions of the operating lever.

It will thus be seen that I have provided a 10 clutch mechanism which may be thrown into operation by simply depressing a lever and which is automatically disengaged when the counter-shaft has made a half-revolution.

The cross-head 6 is also mounted for vertical motion on the guides 4, the downward motion of the cross-head being given to the same by the rods 60, connected to ears 38 at the ends of said cross-head and also connected to the cross-piece 61, the said cross-piece being operated by means of the foot-lever 62, which is connected thereto by the link 63. The upward motion of the cross-head is derived from the springs 64, which surround the guides 4 and abut at one end against collars 25 or similar abutments 65, fixed on the rods, and at their other end against the under side of the cross-head 6.

The operation of the parts thus far described is as follows: A last having a shoe 30 lasted thereon, to which shoe an insole is attached, as shown at 66 in Fig. 1, is placed on the jack and a sole-blank 170, which has not been either molded or rounded, is placed on the former 5, the sole-blank and the bottom of the shoe both having a coating of suitable adhesive applied thereto, as usual, and the former and shoe are then brought together and sufficient pressure applied to mold the sole and attach it to the shoe by the same 35 operation. This is accomplished by first depressing the lever 62, which through the links 60 operate to depress the cross-head 6, and thereby bring the shoe on the jack in contact with the former 5. The lever 46 is then depressed, allowing the spring 49 to cause the clutch members to engage, whereby the shaft 36 is given a half-rotation, as above described, and the support 20, and consequently the former 5, is raised to its extreme upper position, this operation causing the jack with the last applied thereto to yield vertically against the action of the springs 16. I would here remark that the said springs 16 are of sufficient strength so that the pressure applied to the 45 sole through the jack is sufficient to mold the same to the proper shape and to properly attach the same to the shoe. In order to prevent the cross-head 6 from yielding upward while the former is being raised to lay the sole, I 50 have provided suitable clamping mechanism between the cross-head and the guides 4, which clamping mechanism is so constructed as to admit of a free downward movement of the cross-head, but to automatically lock the cross-head from upward motion. As shown in Fig. 1, the links 60 are attached to the ears 38 on the sleeves 70, which surround the upper

ends of the guides 4, the sleeves 70 being integral with the cross-head 6, as seen in Fig. 11. Each sleeve is provided with a radial slot 70

69, in which is pivotally mounted a spring-pressed friction-dog 71, having a nose 72, which bites against the guide 4, and thus prevents the sleeve from moving upward, but allows the free downward movement thereof.

75

By releasing the nose 72 by means of the handle 70' on the lever it will be evident that the cross-head can move upward under the influence of the springs 64 when it is desired to remove the shoe from the jack. While the 80 shoe is pressed against the former to thereby mold the sole-blank and attach the same to the shoe, a suitable knife is thrown in operation to round the sole, the knife moving completely around the shoe and being guided 85 in its movements by the last, whereby the knife operates to round the sole to the shape of the last. At the same time that the sole is rounded a channeling-knife operates to cut the usual channel in the bottom of the sole.

90

Heretofore one common practice has been to round the sole to a pattern before the same is applied to the shoe; but this practice has necessitated the use of right-and-left patterns corresponding to the various sizes and 95 shapes of lasts. With my mechanism, whereby the rounding of the sole is accomplished while the sole is clamped between the former and the shoe, the sole is rounded to the shape of the last and no patterns are required.

100

This I regard as an important feature of my invention, and as I believe that I am the first to accomplish this I claim the same broadly. The means whereby this rounding of the sole to the shape of the last is accomplished is as 105 follows:

A suitable guide-plate 23, having lugs 24, which are sleeved over the uprights 4, is carried by the support 20 for the former, and the said guide-plate 23 has a suitable central opening which contains the plate 29,

110

above described, the plate 29 and inner wall of the opening in the guide-plate 23 forming between them a guideway 84 for the knife-carriage 105, presently to be described. As seen in Fig. 9, this guideway 84 has the 115 general shape of a shoe-sole, but is so constructed that it can be used in rounding either right or left soles. The carriage 105, on which is yieldably supported a knife, rests on the guide-plate 23 and is moved 120 around the shoe by mechanism hereinafter described, the said carriage being guided in its movement by the guideway 84, while the knife, which is supported on said carriage for sliding movement in a direction at right angles 125 to the direction of movement of the carriage, is guided by the last, and its movement operates to cut or round the sole to the shape of the last, as hereinafter described. The operating means for the carriage comprises the 130 sprocket-chain 85, arranged on the under side of the plate 23 and carrying suitable lugs 86, which pass up through the guideway 84 and are guided in their movement thereby, the

lugs having attached thereto the carriage 105 for the knife. The sprocket-chain passes around the sprocket-wheels 88, which are mounted for turning movement upon the 5 posts 27 28, which connect the plate 29 to the support 20. One of the sprocket-wheels 88 has integral therewith a bevel-gear 89, meshing with bevel-gear 90 on the short shaft 91, suitably journaled on the support 20, and the 10 said shaft carries at its outer end a bevel-gear 92, which meshes with a corresponding gear 93 on the vertical shaft 94, the said shaft 94 being geared to the driving-shaft 95 by a suitable system of gearing, such gearing in this 15 embodiment of my invention being shown as a bevel-gear 96 on the lower end of shaft 94, which meshes with a corresponding gear at the end of a short counter-shaft 97, suitably journaled in the frame 3. The shaft 97 carries at one end the bevel-gear 98, which meshes in turn with the gear 99, fast on the shaft 95. A loose driving-pulley 100 is carried by the 20 shaft 95 and is adapted to be clutched thereto by any suitable clutch mechanism, such clutch 25 mechanism being shown in Fig. 4 as a friction-clutch 101. A rock-shaft 103, suitably mounted on the frame of the machine, has at one end the fork 104, which engages a groove 105 in the movable clutch member, and the 30 said rock-shaft carries at its opposite end the treadle 102, by means of which the clutch members can be brought into engagement. Any suitable means (not shown) may be employed to cause the disengagement of the 35 clutch when the said treadle is released. With the driving mechanism thus described it will be obvious that whenever the clutch 101 is thrown into engagement the sprocket-wheels 88 will be revolved, thereby carrying the knife- 40 carriage around the shoe, this movement of the knife-carriage operating to both round the sole and to channel the same, as herein-after described.

In order to allow of the requisite vertical 45 movement of the former-support 20, I make the shaft 94 a two-part shaft, the upper part 90' telescoping in the lower part 94', this arrangement allowing the support with the gearing thereon to be raised or lowered without 50 breaking the operative connection between the drive-shaft and the sprocket-chain. The two parts of the shaft 90' and 94' may be connected together in any suitable way, so that the rotation of the shaft 94' will drive 90', and, 55 as illustrated, the shaft 90' carries the pin 91', which plays in a slot 92' in the shaft 94'. By this construction the two parts of the shaft may have a relative longitudinal movement, but are locked together so as to rotate in unison. 60

Referring now to Figs. 6, 7, and 8, which show in detail a suitable form of sole rounding and channeling mechanism, 105 is the carriage to which the posts or lugs 86, carried 65 by the sprocket-chain 85, are rigidly connected, the said carriage being supported for sliding movement on the top of the guide-

plate 23 and being guided in its movement by the guideway 84, as previously explained. This carriage 105 has yieldably mounted 70 thereon both a rounding-knife and a channeling-knife, and for this purpose it is provided with a suitable guideway 100, in which is mounted for sliding movement in a direction radial to the path of travel of the carriage a spring-pressed slide 106, the said slide having the flanges 177, which play in suitable grooves in the base 105 (see Fig. 8) and being held in its operative position by means of the springs 121, which are fast at 80 one end to the base 105 of the carriage and at the other end to the slide. (See Fig. 7.) The inner end of the slide carries a suitable knife 107, provided with a cutting edge 107', the said knife having a limited turning motion about a vertical axis in order that the knife may accommodate itself to the curvature of the sole as the carriage passes around the shoe. As illustrated, the knife-head 108 has the cylindrical projection 109, which sets 90 in a suitable socket in the slide 106, as shown in dotted lines in Fig. 8, and the said projection 109 has a radially-projecting pin 111 screwed therein, which pin projects through and plays in a slot 110 in the slide 106, this 95 pin serving to limit the turning motion of the knife, as will be obvious, and also preventing the knife from being withdrawn.

In order to support the under side of the sole as the knife is traveling around the same, 100 I have provided the guide-support 113, this being shown in the nature of a block having the projection 114, seated in a suitable recess in the slide 106, and preferably I employ a spring 115 in the bottom of the recess, which serves to maintain the guide-support against the under side of the sole. The guide 113 carries at its upper end the roll 116, which bears against the under side of the sole and serves to support the same as it is being cut 110 into shape. As stated above, the last operates as a pattern-surface to give the proper shape to the sole, and this is accomplished by means of a guide-wheel 117, which is mounted for turning movement upon an arm 118, pivotally mounted, as at 119, on the slide 106. A suitable spring 120 serves to hold the lever 118 in its operative position. Referring to Fig. 6, it will be seen that the said guide-wheel is cone-shaped, and in operation the 115 conical surface thereof rests on the top of the sole, while the base of the cone abuts against the shoe on the last, the springs 121 serving to hold the guide-wheel in constant contact with the shoe as the carriage is propelled 120 around the shoe.

The dotted lines in Fig. 6 show the position of the sole and shoe-upper relative to the knife-carriage, and, as illustrated, the sole during the rounding process rests upon the 130 guide-roll 116, and the spring 120 serves to clamp the sole between the guide-wheel 117 and the guide-roll. Suitable guides 123 rising from the slide 106 and disposed on oppo-

site sides of the lever 118 serve to hold the said lever against lateral movement.

From the above description it will be seen that as the clutch 101 is thrown in operation 5 the bevel gear-wheel 89 will be driven through the mechanism above described to thereby rotate the sprocket-wheels and sprocket-chain 85, the said sprocket-chain, through the lugs 86, propelling the knife-carriage around the 10 shoe and the guideway 84 guiding the carriage in its movement. The knife 107 being carried on the slide 106 has a movement independent from the carriage, and, as stated above, the springs 121 serve to keep the slide 15 toward the inner end of the carriage, and thus maintain the constant contact of the guide-wheel 117 with the shoe-upper on the last, and hence as the knife-carriage travels around the shoe the guide-wheel follows exactly the 20 shape of the last, and therefore gives to the slide 106, upon which the knife 107 is mounted, requisite movement relative to the carriage to round the sole exactly to the shape of the last. With my machine, therefore, it 25 is not necessary to provide special pattern-surfaces or templets for use in rounding the sole, as the last itself performs this function. When the knife-carriage has passed completely around the shoe, the foot-treadle 102 30 may be released to cause the disengagement of the clutch members 100 101, and thereby stop the movement of the knife-carriage.

In placing a shoe upon the jack or removing it therefrom and in placing the sole-blank 35 upon the former it is necessary to move the knife and guide-wheel out of the way of the sole, and this is accomplished by means of the lever 130, which is pivoted at one end to the knife-carriage, as at 131, and bears inter- 40 mediate its length against the uprights 132, to which the lever 118 is pivoted. By moving the lever to the right in Fig. 7 it will be evident that the slide 106 will be retracted against the action of the springs 121, thereby 45 moving the knife and guide-wheel out of the way of the shoe or its sole.

Any suitable means may be employed to hold the lever in its retracted position, and in Figs. 6 and 7 I have illustrated the spring- 50 catch 133, which engages the lever and holds it retracted. I have also provided means whereby the sole is channeled at the same time that it is rounded, this being done by the channeling-knife 134, which is also yield- 55 ably supported on the carriage, preferably by mounting it upon the guide-support 113, which is supported on the slide 106. For this purpose the said guide-support has the offset portion 135, in which the shank 136 of the 60 said channeling-knife is adjustably mounted and held in its adjusted position by the set-screw 133. The knife will of course be so adjusted that its cutting edge 138 will be slightly above the top of the roll 116, and, as illus- 65 trated, the outside edge of the knife is in substantially the same plane as the cutting edge of the rounding-knife 107, whereby the chan-

nel will be cut in the sole from the outside edge thereof.

It is essential that the channeling-knife 70 have a slight turning movement on a vertical axis to accommodate itself to the turning movement of the knife-carriage in passing around the sole, and this may be accomplished in any suitable way. As illustrated, the shank 75 114 of the guide-support 113 is provided with a radially-projecting pin 140, which plays in the slot 141 in the slide 106. The slot is slightly wider than the pin, thus allowing for the necessary turning movement of the channeling-knife. It will be obvious, of course, that other ways of providing for this turning movement may be used instead of that shown.

As stated above, the jack which supports the last is yieldingly mounted, this construction being made necessary, because in using the knife-carriage in connection with the former for rounding the sole it is necessary that the former and knife have a definite relative position to each other, and therefore instead of making the former yieldingly mounted I have made my jack vertically yieldable.

From the above description it will be seen that I have combined in a single machine mechanism which is adapted to mold a sole-blank between the former and a last and at the same time attach the same to the shoe, and while the sole is thus clamped between the former and shoe mechanism is set in operation which rounds the sole, using the last 100 as a pattern.

Simultaneously with the rounding of the sole the sole is channeled, and all these operations are performed upon the shoe without taking the same from the machine.

Various modifications may be made in the structure of my device without departing from the spirit of the invention, and I therefore reserve the right to make such changes as come within the scope of the claims.

Having fully described my invention, what I claim as new, and desire to secure by Letters Patent, is—

1. In a machine of the class described, a yieldingly-mounted jack to support a lasted shoe, a rigidly-mounted former, said former having a contour substantially the same as the sole of a shoe, and having one face shaped to fit the bottom of the last, and means to move one of said parts relative to the other, whereby the sole may be molded between the lasted shoe and former, combined with sole-rounding mechanism to round the sole while clamped between the former and lasted shoe.

2. In a machine of the class described, a yieldingly-mounted jack to support a lasted shoe, a rigidly-mounted former having one face shaped to fit the bottom of the last, means to move the jack to bring the last in contact with the former, means to subsequently move the former against the lasted shoe on the yielding jack, whereby a sole placed between the former and lasted shoe may be molded to the shape of the last combined with sole-

rounding mechanism to round the sole while clamped between the former and the shoe.

3. In a machine of the class described, a yieldingly-mounted jack to hold a last, a support, a former rigidly carried thereby, means to clamp a sole-blank between the shoe on the last and the former, the said former being detachably mounted on the support, whereby either right or left soles may be molded and laid.

4. In a machine of the class described, a yieldingly-mounted jack to hold the last, a support, a former rigidly carried thereby but detachably therefrom, whereby either right or left formers may be used, said formers having one face shaped to fit the bottom of the last, means to move the jack to bring the last in contact with the former, and means to subsequently move the former against the last and the yielding jack, whereby a sole placed between the former and last may be molded to the shape of the last.

5. In a machine of the class described, a cross-head, guideways therefor, a jack yieldingly carried by said cross-head and adapted to support a last, a former, means to lower the cross-head to bring the shoe on the last in contact with the former, means to lock the cross-head in its lowered position, and means to raise the former against the last on the yielding jack, whereby a sole may be molded between the former and shoe, and at the same time attached to the shoe.

6. In a machine of the class described, a yieldingly-sustained jack to hold a last, a rigidly-mounted former having one face shaped to fit the bottom of the last, means for forcing the former against the last, said means including a shaft, an eccentric thereon, connections between the eccentric and former, clutch mechanism to rotate the shaft and means to automatically disengage said clutch mechanism, when the former has reached the upward limit of its movement.

45 7. In a machine of the class described, a non-rotatable jack to support a last, a former having one face adapted to fit the bottom of the last, means to clamp a sole-blank between said former and last, and sole-rounding mechanism to round the sole while between the former and last, rounding mechanism including a knife mounted for turning movement.

8. In a machine of the class described, a non-rotatable yieldingly-mounted jack to support a last, a former having one face adapted to fit the bottom of the last, means to clamp a sole-blank between said former and last, and sole-rounding mechanism to round the sole while between the former and last.

60 9. In a machine of the class described, a jack adapted to support a lasted shoe, a former, means to clamp a sole-blank between the former and lasted shoe, and sole-rounding mechanism, said mechanism being guided by the last, and having a knife supported for turning movement.

10. In a machine of the class described, a

jack to support a last, a former, means to clamp the sole between the former and last, a cutting mechanism, means to carry the same around the shoe, and means controlled by the last for guiding said cutting mechanism whereby the sole is rounded to the shape of the last.

11. In a machine of the class described, a jack to support a lasted shoe, a former, means to clamp sole-blanks between the former and last, a carriage supporting a knife, means to propel the carriage around the sole, and means controlled by the last to guide the knife, whereby the sole is rounded to the shape of the last.

12. In a machine of the class described, a jack to support a lasted shoe, a former, means to clamp sole-blanks between the former and last, a carriage supporting a knife, means to propel the carriage around the sole, and means controlled by the last to guide the knife, the said knife having a turning movement relative to the carriage.

13. In a machine of the class described, a jack to support a last, a former, a carriage, a guideway therefor extending around the shoe, a slide on the carriage, a knife on said slide, and means controlled by the last to guide the knife.

14. In a machine of the class described, a jack forming a support for the last, a former, means to clamp a sole-blank between the last and former, a carriage, a slide carried thereby and supporting a knife, a guide on the slide adapted to contact with the shoe on the last, means to propel the carriage around the shoe, whereby the knife rounds the sole to the shape of the last.

15. In a machine of the class described, a jack, forming a support for the last, a former, means for clamping a sole-blank between the former and shoe on the last, a carriage, a slide carried thereby and supporting a knife, a guide on the slide, means to propel the carriage around the shoe, and means to maintain the contact of the guide with the shoe on the last, whereby the knife rounds the sole to the shape of the last.

16. In a machine of the class described, a jack forming a support for the last, a former, means for clamping a sole-blank between the former and shoe on the last, a carriage, a slide carried thereby, a knife supported for turning movement on the slide, means to propel the carriage around the shoe, and means to maintain the contact of the guide with the shoe on the last, whereby the sole is rounded to the shape of the last.

17. In a machine of the class described, a jack to support a last, a former having one face shaped to fit the bottom of the last, means to clamp and mold a sole-blank between the former and the shoe on the last, a carriage, a slide mounted thereon for movement at right angles to the direction of movement of the carriage, a knife on the slide, means to propel the carriage around the shoe, and means

controlled by the last to guide the knife, whereby the sole is rounded to the shape of the last.

18. In a machine of the class described, a jack to support a last, a former having one face shaped to fit the bottom of the last, means to clamp and mold a sole-blank between the former and the shoe on the last, a carriage, a guideway therefor extending around the shoe, a slide mounted on the carriage for movement at right angles to the direction of movement of the carriage, said slide carrying a support for the under side of the sole, and a knife for rounding the sole, means to propel the carriage around the shoe, and means governed by the last controlling the movements of the slide, whereby the sole is rounded to the shape of the last.

19. In a machine of the class described, a jack to support a last, a former, means to clamp and mold a sole-blank between the former and shoe on the last, a carriage, a guideway therefor, a slide on the carriage, and mounted for movement at right angles to the direction of movement of the carriage, said slide carrying a sole-rounding knife and a guide-wheel adapted to contact with the shoe on the last, means to propel the carriage around the shoe, and means to preserve the contact of the guide-wheel with the shoe, whereby the sole is rounded to the shape of the last.

20. In a machine of the class described, a jack supporting a last, a former, means to clamp and mold a sole-blank between the former and the shoe on the last, a carriage, a slide carried thereby and mounted to move at right angles to the direction of movement of said carriage, said slide carrying a support for the under side of the sole, a knife and a pivotally-mounted guide-wheel adapted to rest on top of the sole and contact with the shoe on the last, means to propel the carriage around the shoe, and means to preserve the contact of the guide-wheel with the shoe, whereby the sole is rounded to the shape of the last.

21. In a machine of the class described, a jack forming a support for the last, a former, means to clamp and mold a sole-blank between the former and the shoe on the last, a carriage, said carriage having mounted thereon a support for the under side of the sole, a knife, and a guide adapted to rest on the top of the sole, and bear against the shoe on the last, means to propel the carriage around the shoe, and means to maintain the contact of the guide with the shoe, whereby the sole is rounded to the shape of the last.

22. In a machine of the class described, a jack supporting a last, a former, means to clamp a sole-blank between the former and last, sole-rounding mechanism, said mechanism being guided by the last, and sole-channeling mechanism.

23. In a machine of the class described, a jack supporting a last, a former, means to clamp a sole-blank between the former and

the shoe on the last, a carriage supporting sole rounding and channeling knives, means to propel the carriage around the sole, and means controlled by the last to guide said knives.

24. In a machine of the class described, a jack supporting a last, a former, means to clamp a sole-blank between the former and the shoe on the last, a carriage supporting sole rounding and channeling knives, means to propel the carriage around the sole, and means controlled by the last to guide said knives, each of said knives having a turning movement, whereby they may be adapted to the curvature of the sole.

25. In a machine of the class described, a jack supporting a last, a former, means to clamp the sole between the former and the shoe on the last, a carriage supporting a sole-rounding knife, and a channeling-knife, said channeling-knife being adjustable, means to propel the carriage around the sole, and means controlled by the last to guide the said knives.

26. In a machine of the class described, a jack supporting the last, a former, means to clamp a sole-blank between the former and the shoe on the last, a carriage, a guide therefor extending around the sole, a slide on the carriage, sole rounding and channeling knives mounted on the slide, and means to propel the carriage around the shoe, and means controlled by the last to guide the knives.

27. In a machine of the class described, a jack supporting the last, a former, means for clamping a sole-blank between the former and the shoe on the last, a carriage, a slide carried thereby, a sole-rounding knife and a channeling-knife mounted on the slide, a guide also mounted on the slide and adapted to contact with the shoe on the last, means to propel the carriage around the shoe, and means to maintain the constant contact of the guide with the shoe on the last.

28. In a machine of the class described, a jack supporting a last, a former, means to clamp a sole-blank between the former and the shoe on the last, a carriage, a slide carried thereby, a sole-rounding knife and an adjustable channeling-knife mounted on the slide, a guide also carried by the slide and adapted to contact with the shoe on the last, means to propel the carriage around the shoe, and means to maintain the constant contact of the guide with the shoe on the last.

29. In a machine of the class described, a jack supporting a last, a former, means to clamp a sole-blank between the shoe on the last and the former, a carriage, a guideway therefor, a slide carried thereby, and mounted to move at right angles to the direction of movement of the carriage, a sole-rounding knife, and an adjustable channeling-knife mounted on the slide, a guide-wheel pivotally mounted on the slide, and adapted to rest on the top of the sole and contact with the shoe on the last, means to propel the carriage around the shoe, and means to preserve the

constant contact of the guide-wheel with the shoe on the last.

30. In a machine of the class described, a jack supporting a last, a support, a former carried thereby, means to clamp a sole-blank between the shoe on the last and the former, the said former being detachably mounted on the support, whereby either right or left formers may be used, a cutting mechanism sustained by said support, said cutting mechanism including a knife, means to move the cutting mechanism around the sole, and means controlled by the last to guide the knife whereby the sole is rounded to the shape of the last.

31. In a machine of the class described, a jack to support a last, a support, a former detachably carried thereby, whereby either right or left formers may be used, means to clamp a sole-blank between the shoe on the last and the former, a carriage mounted on the support and guided thereby, a slide on the carriage movable at right angles to the direction of movement of the carriage, said slide carrying a knife and a guiding means adapted to contact with the shoe on the last, means to move the carriage around the shoe, and means to preserve the contact of the guiding means with the shoe whereby the sole is rounded to the shape of the last.

32. In a machine of the class described, a jack supporting a last, a support, a former detachably carried thereby, whereby either right or left formers may be used, means to clamp a sole-blank between the shoe on the last and the former, sole-rounding mechanism mounted on said support and including a knife, means to move said knife around the sole, sole-channeling mechanism operated in unison with the sole-rounding mechanism, and means controlled by the last to guide both the sole-rounding and sole-channeling mechanisms, whereby the sole is rounded to the shape of the last.

33. In a machine of the class described, a jack supporting the last, a support, a former detachably carried thereby, whereby either right or left formers may be used, means to clamp a sole-blank between the shoe on the last and the former, a carriage mounted on the support and guided thereby, a sole-rounding knife and an adjustable channeling-knife

each knife yieldably mounted on said carriage, a guide on the carriage and adapted to contact with the shoe on the last, means to move the carriage around the shoe, and means to preserve the contact of the guide with the shoe, whereby the sole is rounded to the shape of the last.

34. In a machine of the class described, a jack to support a lasted shoe, a former, a carriage, a guideway therefor extending around the shoe, a knife yieldably mounted on said carriage, means to move the carriage around the shoe, and means controlled by the last to guide the knife.

35. In a machine of the class described, a non-rotatable jack to support a lasted shoe, rounding mechanism including a carriage, a rounding-knife yieldably supported thereon, means to propel the carriage around the shoe, and means controlled by the last to guide the knife, whereby the sole is rounded to the shape of the last.

36. In a machine of the class described, a non-rotatable jack to support a lasted shoe, channeling mechanism including a carriage, a channeling-knife yieldably supported thereon, means to propel the carriage around the shoe, and means controlled by the last to guide the knife.

37. In a machine of the class described, a non-rotatable jack to support a lasted shoe, rounding and channeling mechanisms including a rounding-knife and a channeling-knife, and means controlled by the last to guide each of said knives.

38. In a machine of the class described, a non-rotatable jack to support a lasted shoe, rounding and channeling mechanisms including a carriage, a rounding-knife and a channeling-knife yieldably supported thereon, means to propel the carriage around the shoe, and means controlled by the last to guide the said knives.

In testimony whereof I have signed my name to this specification in the presence of two subscribing witnesses.

WALTER H. CLARK.
